UNITED STATES PATENT OFFICE.

WILHELM SCHÖNDELING, OF ESSEN-ON-THE-RUHR, GERMANY.

PROCESS OF AND DEVICE FOR QUENCHING COKE IN NARROW CONTAINERS.

1,421,777.

Specification of Letters Patent. Patented Aug. 8, 1922.

Application filed May 12, 1920. Serial No. 330,934.

To all whom it may concern:

Be it known that I, WILHELM SCHÖNDELING, a citizen of Germany, and residing at 89 Alfredstrasse, Essen-on-the-Ruhr, Germany, have invented certain new and useful improvements in Processes of and Devices for Quenching Coke in Narrow Containers (for which I have filed an application in Germany August 21, 1915, Patent Number 298,102, issued March 27, 1917), of which the following is a specification.

My invention relates to a process of, and a device for, quenching and loading coke, resulting in obtaining a good quenching effect while the coke is preserved during the quenching and loading operation. According to the invention, the cake of coke discharged from the coke oven is received in a container corresponding in its size to the dimensions of the coking chamber. For the reception of the coke the container is turned on one of its narrow side walls, and, thereafter, laid flat on a broad side wall for the quenching operation. One of its broad walls is preferably pierced to enable the quenching to be effected by a water shower from without. Since in the horizontal position the cake of coke offers a very large surface and but a small thickness, the quenching is obtained under favourable conditions in a very short space of time and by means of a comparatively small quantity of water. The quenching water may be enabled to rise within the container. The steam developing during quenching is able to quickly escape and will partly be condensed through the action of the quenching shower. The cake of coke encased in the container is preserved during this treatment.

The discharge of the container may be effected by means of a rammer or by means of a scraper actuated by traction members. However, the container may be given an oblique disposition, in one direction or another, so that the cake of coke, when the respective narrow side wall is removed, will slide out of its own accord and pass over a screen or a slide way and drop into a railway car, or upon a conveying device. In order to be able to pile the coke within the least space and simultaneously preserve the coke as far as possible, the container may be removed to the storing place by means of a suitable lifting device and the cakes of coke piled there one upon the other through

the opening of a broad container wall previously removed.

The container receiving the cake of coke is preferably pivotally or revolvably mounted upon a movable frame, as for instance, upon a frame that is revolvably supported on a carriage.

In the drawings a constructive form of the device is illustrated. Figure 1 shows the device in the position in which the cake of coke is being transferred from the coke oven into the device. Figure 2 shows the device during the quenching operation, and Figure 3 after the quenching operation and previously to the loading operation.

The device consists of a platform *a* having two side walls which may be completed to a container by means of the closing doors *b* and *b'*. In conjunction with the pierced wall *c* and the closing door *b'*, the platform forms a closed chamber which is open towards the coke oven and adapted to receive the cake of coke in unbroken condition. The turning of the cake of coke for approximately 90 degrees may be effected by means of a motor or manually, by rolling the platform upon the rolls *e*. The revolution of the chamber may obviously be carried out in any other manner. *f* designates the discharge branch for the spent quenching water and adapted to be shut. *g* is the movable carriage upon which the device may be transferred to any place in front of the battery of ovens. *h* is the conduit for the quenching water, and *i* a screen or a slide way for loading purposes.

The mode of operation is as follows: The platform placed upright and open towards the side of the ovens, is moved in front of the oven and the cake of coke is pressed into the same. Thereupon the platform is turned into a horizontal position, closed by means of the closing door *b*, and charged with quenching water by means of the showering pipe *h*, until the coke mass is completely quenched. The removal of the quenching water not evaporated is effected through the discharge *f* by inclining the platform somewhat after opening the discharge *f* in order to obtain the fall required for the discharge. The spent quenching water is either allowed to run to waste or is pumped into a suitable storing vessel to be reused.

What I claim as my invention and desire

to secure by Letters Patent of the United States, is:—

1. A revolvably mounted quenching chamber for coke and similar materials having a bottom wall, fixed side walls, movable closing doors transverse to said side walls, an apertured upper wall to permit the passage of a liquid spray, and means for removing the excess water from the chamber.
- 10 2. A revolvably mounted quenching chamber for coke and similar materials having a bottom wall, fixed side walls, movable closing doors transverse to said side walls, an upper wall having a plurality of apertures to permit the passage of a liquid spray, and means for removing the excess of liquid from the chamber.
- 15 3. A revolvably mounted quenching chamber for coke and similar materials, supported on a movable carriage, having a bottom wall, fixed side walls, movable closing doors, transverse to said side walls, an apertured upper wall to permit the passage of a liq-

uid spray, and means for removing the excess liquid from the chamber.

25 4. A quenching chamber adapted to hold narrow cakes of coke, having a bottom wall, fixed side walls, movable closing doors transverse to said side walls, an apertured upper wall to permit the passage of a water spray, and means for removing the liquid from the chamber.

30 5. The process of treating cakes of coke having narrow and broad sides, comprising receiving the cake from a coking chamber into a quenching chamber on a side of small width, and thereafter positioning it on one of its broad sides to permit quenching water to adequately penetrate the coke.

35 In testimony that I claim the foregoing as my invention, I have signed my name in presence of two subscribing witnesses.

WILHELM SCHÖNDELING. [L. S.]
